UNITED STATES PATENT OFFICE.

JOSEPH RECHICHAR, OF PLYMOUTH, PENNSYLVANIA, ASSIGNOR OF FORTY-FIVE PER CENT TO WILLIAM B. CLEARY, OF PLYMOUTH, PENNSYLVANIA.

MINING MACHINE.

Application filed September 21, 1922. Serial No. 589,622.

To all whom it may concern:

Be it known that I, JOSEPH RECHICHAR, a citizen of the United States of America, residing at Plymouth, in the county of 5 Luzerne and State of Pennsylvania, have invented certain new and useful Improvements in Mining Machines, of which the following is a specification.

This invention relates to certain new and 10 useful improvements in mining machines and has particular reference to a portable apparatus especially designed for the mining of coal, the coal being chipped or broken from a standing wall by a portable device 15 that is manually operable.

A further object of the invention is to provide a mining machine of the portable type wherein a combined rotating and reciprocably mounted cutter blade is associated with a screw device for removing the coal and dust from an opening formed by the machine.

With the above general objects in view and others that will appear as the nature 25 of the invention is better understood, the same consists of the novel form, combination and arrangement of parts hereinafter more fully described, shown in the accompanying drawings and claimed.

30 In the drawings, wherein like reference characters designate corresponding parts throughout the several views,

Figure 1 is a side elevational view of a mining machine constructed in accordance 35 with the present invention showing the gear rotated screw casing supporting the reciprocal and rotary cutting blades,

Figure 2 is a longitudinal sectional view taken on line II—II of Fig. 1 showing the 40 reciprocating mechanism for the cutter blade supporting rod and the adjustable breast plate,

Figure 3 is a longitudinal sectional view taken on line III—III of Fig. 1,

45 Figure 4 is a fragmentary sectional view of a portion of the machine showing the tensioned reciprocating rod within the rotatable screw casing supporting the centering drills and the reciprocating cutter blades,

50 Figure 5 is a fragmentary side elevational view of the outer end of the rotating screw casing supporting the cutter blades,

55 Figure 6 is a cross sectional view taken on line VI—VI of Fig. 5 showing the cen-

tering drill anchored to the outer end of the screw casing,

Figure 7 is a fragmentary side elevational view, similar to Fig. 5,

Figure 8 is a fragmentary perspective 60 view of the outer end of the screw casing,

Figure 9 is a perspective view of the cutter blades,

Figure 10 is a fragmentary perspective 65 view of the centering drill, and

Figure 11 show perspective views of the clamping block and retaining plate for the centering drill.

Referring more in detail to the accompanying drawings, there is illustrated a 70 mining machine of the portable type embodying a rectangular casing having a rear wall 1, end walls 2 and 3, side walls 4 and 5 and a removable front wall 6, the casing enclosing the operating mechanism for the 75 cutter blades. An arcuate breast plate 7 is associated with the end wall 3 of the casing, the same being shown more clearly in Figs. 1 and 2 and includes a central stub shaft 8 swiveled in the boss 3^a carried by the end 80 wall 3 of said casing and retained in adjusted positions relative to said casing by the screw 9 entering the groove 8^a formed in the inner end of said stub shaft, the screw passing radially through the end wall of the 85 casing.

As shown in Figs. 1, 2 and 3, an apertured bearing 10 is formed integral with the end wall 2 of the casing and extends inwardly thereof, a sleeve 11 extending through said slot and end wall 2, being rotatable therein and having a beveled gear 12 secured to the inner end thereof within the casing. To retain the rotatable sleeve 11 properly positioned, a tubular screw casing 13 carrying 90 a spiral blade 14 encloses the outer projecting end of said sleeve and is anchored thereto by the set screw 15, the screw casing 13 being rotatable with said sleeve 11. The outer end of the screw casing 13 with the 95 spiral blades 14 removed is shown in Figs. 5 to 8, said tubular casing having crossed slots 16 and 17, the slots 17 being of greater depth than the slots 16 for purposes presently to appear.

A sectional rod is reciprocably mounted within the rotatable screw casing 13, said rod embodying a middle section 18 threaded at its outer end to the outer section 19, while the inner end thereof is linked as at 20 to 110

the inner section 21. The sectional rod is resiliently mounted within the screw casing 13 for normally occupying a position at its limit of outward movement, the coil spring 5 22 surrounding the central rod section 18 being anchored at the outer end thereof as at 23 to the casing 13 while the inner end of said spring is anchored as at 24 to the rod section 18, this construction being clearly 10 shown in Fig. 4. A cutter blade embodying bifurcated blade sections 25 includes a tapering shank 26 that is received in the tapered socket 27 formed in the outer end of the rod section 19, the inner ends of the cutter blades 15 25 being disposed in the relatively long slots 17 in the outer end of the screw casing 13. A centering drill 28 is supported at the outer end of the screw casing 13, said drill being provided with a block 29 at the inner 20 end thereof having rack teeth 30 upon one side face, the block 29 of the centering drill being mounted in the supporting arm 31 shown in detail in Fig. 11, the arm 31 having a side socket 32 with the rear wall there- 25 of provided with rack teeth 33 to cooperate with the rack teeth 30 upon the drill block 29, said drill being retained in the arm 31 by the plate 34. The arm 31 and plate 34 are provided with registering openings 35 30 adjacent each end thereof, said arm being disposed in the slot 16 at the outer end of the screw casing 13, one end thereof being anchored within the screw casing by the rivets 36 passing through the registering 35 openings 35 and openings 17^a in the outer end of the screw casing. A removable cotter pin 37 anchors the opposite end of the arm and plate to the screw casing as shown in Fig. 6. It will therefore be seen that the center- 40 ing drill 28 is immovable relative to the screw casing 13, while the cutter blades 25 carried by the link rod section 19 are reciprocable within the space between the lower ends of the slots 17 and the inner edge of 45 the arm 31.

The rotating and reciprocating mechanism for the screw casing 13 and the link rod includes a cross arm 38 positioned within the mechanism casing and having the 50 ends thereof projecting between guides 39. The link rod section 21 centrally extends through the cross arm 38, the same carrying a bearing nut 40 threaded upon the lower end of said rod section with bearing balls 41 55 interposed between the nuts 40 and the cross arm 38, reducing friction when the screw casing 13 and link rod rotate relative to said cross arm 38. As shown more clearly in Figs. 1 to 3, a rock shaft 42 is journaled 60 at its opposite ends in the side walls 4 and 5 of the mechanism casing adjacent the end wall 3, the rock shaft carrying a centrally positioned radial lug 43 having a link connection 44 with the crotch of a substantially 65 V-shaped frame 45, the ends 45^a of which

are received in sockets 46 formed in the lower face of the cross arm 38 as shown in Fig. 4. An end radial lug 47 is carried by the rock shaft 42 and pivotally supports a link arm 48, the latter being guided by a 70 strap bearing 49 shown in Figs. 1 and 2 while the free upper end thereof carries a laterally projecting finger 50 that extends into a side slot 51 formed in the bearing block 10 and clearly shown in Figs. 1 and 3. 75 A stub shaft 52 is journaled through the side wall 4 of the mechanism casing adjacent the outer end thereof, the frame supporting upon its inner end, a beveled gear 53 that meshes with the bevel gear 12 upon the sleeve 80 11, the outer projecting end of said shaft being provided with an adjustable crank handle 54 to effect rotation thereof. A star wheel 55 is fixed to the stub shaft 52 within the mechanism casing and is disposed for 85 engagement with the finger 50 upon the link arm 48.

In the operation of the device, the breast plate 7 is adjusted to accommodate the machine to the person using the same, a handle 90 56 being carried by the side wall 5 for gripping the machine, while the crank handle 54 is rotated for operating the machine. Upon rotation of the stub shaft 52, the points of the star wheel 55 are successively moved into 95 engagement with the finger 50 upon the link arm 48, moving the rock shaft 42 and the cross arm 38 through the guides 39, thereby retracting the sectional link rod within the screw casing 13 and mechanism casing 100 against the tension of the coil spring 22 for retracting the cutter blades 25. When the star points escape the pins 50 upon the link arm 48, the coil spring 22 will forcibly 105 eject the link rod and move the cutter blade 25 into engagement with a wall of coal. During this operation, it being understood that the centering drill 28 carried by the outer end of the screw casing 13 is constantly 110 in engagement with the wall of coal, the meshing gears 53 and 12 will rotate the screw casing 13 together with the sections of the linked rod accommodated by the swivel mounting of the inner end of the rod section 21 with the cross arm 38 as 115 shown in Fig. 4, causing the spiral blade 14 upon the screw casing 13 to enter a cut or drilled hole and by rotation thereof extracting the coal and dust from the opening. The operation of the device is continuous, 120 the screw casing 13 rotating simultaneously with the reciprocating movement of the linked rod and the cutter blades 25 carried thereby. The centering drill 28 and cutter blades 25 are removably mounted in the machine to permit substitution of various sizes of drills and cutters and also for purposes of replacing the same should injury result thereto.

While there is herein shown and described 130

the preferred embodiment of the present invention, it is nevertheless to be understood that minor changes may be made therein without departing from the spirit and scope

5 thereof as claimed.

What I claim is:—

1. In a mining machine, a mechanism casing, a screw casing journaled therein, a rod reciprocably mounted in the screw casing 10 and extending into the mechanism casing, a cutter carried by the outer end of the rod, manually operable mechanism for reciprocating said rod, and a center drill fixed to the outer end of the screw casing.

15 2. In a mining machine, a mechanism casing, a screw casing journaled therein, a rod reciprocably mounted in the screw casing and extending into the mechanism casing, a cutter carried by the outer end of the rod, 20 manually operable mechanism for reciprocating said rod, the connection between the cutter and rod including a socket formed in the outer end of the rod, a shank carried by the cutter extending into said socket and 25 a center drill fixed to the outer end of the screw casing and retaining the cutter in the rod socket.

3. In a mining machine, a mechanism casing, a screw casing journaled therein, a rod 30 reciprocably mounted in the screw casing and extending into the mechanism casing, a cutter carried by the outer end of the rod, manually operable mechanism for reciprocating said rod, a center drill including a 35 cross arm extending across to the outer end of the screw casing, the connection between the cutter and rod including a socket formed in the outer end of the rod and a shank carried by the cutter extending into said socket 40 and positioned inwardly of the drill cross arm.

4. In a mining machine, a mechanism casing, a screw casing journaled therein, a rod reciprocably mounted in the screw casing 45 and extending into the mechanism casing, a cutter carried by the outer end of the rod, manually operable mechanism for reciprocating said rod, the connection between the cutter and rod including a socket formed in 50 the outer end of the rod, a shank carried by the cutter extending into said socket, the outer end of the screw casing having a transverse slot therein and said cutter including side blades extending through the slot.

55 5. In a mining machine, a mechanism casing, a screw casing journaled therein, a rod reciprocably mounted in the screw casing and extending into the mechanism casing, a cutter carried by the outer end of the rod, 60 manually operable mechanism for reciprocating said rod, a center drill fixed to the outer end of the screw casing, the connection between the cutter and rod including a 65 socket formed in the outer end of the rod, a shank carried by the cutter extending into

said socket, the outer end of the screw casing having a transverse slot therein and said cutter including side blades extending through the slot.

6. In a mining machine, a mechanism casing, a screw casing journaled therein, a rod reciprocably mounted in the screw casing and extending into the mechanism casing, a cutter carried by the outer end of the rod, 70 manually operable mechanism for reciprocating said rod, the connection between the cutter and rod including a socket formed in the outer end of the rod, a shank carried by the cutter extending into said socket, the outer end of the screw casing having a transverse slot therein, said cutter including side blades extending through the slot, the connection between the center drill and screw casing including a slot formed in the outer end of the screw casing at right angles to the cutter slot, and an arm removably mounted in the slot supporting the center drill.

7. In a mining machine, a mechanism casing, a screw casing journaled therein, a rod reciprocably mounted in the screw casing and extending into the mechanism casing, a cutter carried by the outer end of the rod, 75 manually operable mechanism for reciprocating said rod, a center drill fixed to the outer end of the screw casing, the connection between the cutter and rod including a socket formed in the outer end of the rod, a shank carried by the cutter extending into said socket, the outer end of the screw casing having a transverse slot therein, said cutter including side blades extending through the slot, the connection between the center drill and screw casing including a slot formed in the outer end of the screw casing at right 80 angles to the cutter slot, and an arm removably mounted in the slot supporting the center drill.

8. In a mining machine, a mechanism casing, a screw casing journaled therein, a rod reciprocably mounted in the screw casing and extending into the mechanism casing, a cutter carried by the outer end of the rod, 85 manually operable mechanism for reciprocating said rod, the connection between the cutter and rod including a socket formed in the outer end of the rod, a shank carried by the cutter extending into said socket, the outer end of the screw casing having a transverse slot therein, said cutter including side 90 blades extending through the slot, a coil spring surrounding the rod, anchored at its inner end thereto and at its outer end to said screw casing and said manually operable mechanism adapted to retract said rod against the tension of said spring to a position to permit the spring to forcibly eject the rod and cutter carried thereby.

9. In a mining machine, a mechanism casing, a screw casing journaled therein, a rod 95

- reciprocably mounted in the screw casing and extending into the mechanism casing, a cutter carried by the outer end of the rod, manually operable mechanism for reciprocating said rod, a center drill fixed to the outer end of the screw casing, the connection between the cutter and rod including a socket formed in the outer end of the rod, a shank carried by the cutter extending into said socket, the outer end of the screw casing having a transverse slot therein, said cutter including side blades extending through the slot, a coil spring surrounding the rod, anchored at its inner end thereto and at its outer end to said screw casing and said manually operable mechanism adapted to 70 retract said rod against the tension of said spring to a position to permit the spring to forcibly eject the rod and cutter carried thereby.
- 10 12. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, said manually operable mechanism including a cross arm slidably mounted in the mechanism casing, swivel connection for the inner end of the rod and the cross arm, a manually rotated stub 75 shaft journaled in a side wall of the mechanism casing, gear connections between the stub shaft and rod, a star wheel fixed to the stub shaft, a link arm slidably in said casing having a pin associated with the star wheel, a rock shaft and link connections between the rock shaft, cross arm and link arm.
- 15 13. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, the connection between the cutter and rod including a socket formed 80 in the outer end of the rod, a shank carried by the cutter extending into said socket, the outer end of the screw casing having a transverse slot therein, said cutter including side blades extending through the slot, a center 85 drill connected to the outer end of the screw casing the connection between the center drill and screw casing including a slot formed in the outer end of the screw casing at right angles to the cutter slot, an arm removably mounted in the slot supporting the center drill, a coil spring surrounding the rod, anchored at its inner end thereto and at its outer end to said screw casing and said 90 manually operable mechanism adapted to retract said rod against the tension of said spring to a position to permit the spring to forcibly eject the rod and cutter carried 95 thereby.
- 20 14. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, a center drill fixed to the outer end of the screw casing, said manually operable mechanism including a cross arm slidably mounted in the mechanism casing, swivel connection for the inner end of the rod and the cross arm, a manually rotated stub 100 shaft journaled in a side wall of the mechanism casing, gear connections between the stub shaft and rod, a star wheel fixed to the stub shaft, a link arm slidably in said casing having a pin associated with the star wheel, a rock shaft and link connections between the rock shaft, cross arm and link arm.
- 25 15. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, the connection between the cutter and rod including a socket formed 105 in the outer end of the rod, a shank carried by the cutter extending into said socket, the outer end of the screw casing having a transverse slot therein, said cutter including side blades extending through the slot, a center 110 drill connected to the outer end of the screw casing the connection between the center drill and screw casing including a slot formed in the outer end of the screw casing at right angles to the cutter slot, an arm removably mounted in the slot supporting the center drill, a coil spring surrounding the rod, anchored at its inner end thereto and at its outer end to said screw casing and said 115 manually operable mechanism adapted to retract said rod against the tension of said spring to a position to permit the spring to forcibly eject the rod and cutter carried 120 thereby.
- 30 16. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, a center drill fixed to the outer end of the screw casing, the connection between the cutter and rod including a socket formed 125 in the outer end of the rod, a shank carried by the cutter extending into said socket, the outer end of the screw casing having a transverse slot therein and said cutter including side blades extending through the slot, said manually operable mechanism including a cross arm slidably mounted in the mechanism casing, swivel connection for the inner end of the rod and the cross arm, a manually rotated stub shaft 130
- 35
- 40
- 45
- 50
- 55
- 60
- 65

removably mounted in the slot supporting the center drill, a coil spring surrounding the rod anchored at its inner end thereto and at its outer end to said screw casing and said manually operable mechanism adapted to 70 retract said rod against the tension of said spring to a position to permit the spring to forcibly eject the rod and cutter carried thereby.

12. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, said manually operable mechanism including a cross arm slidably mounted in the mechanism casing, swivel connection for the inner end of the rod and the cross arm, a manually rotated stub 75 shaft journaled in a side wall of the mechanism casing, gear connections between the stub shaft and rod, a star wheel fixed to the stub shaft, a link arm slidably in said casing having a pin associated with the star wheel, a rock shaft and link connections between the rock shaft, cross arm and link arm.

13. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, a center drill fixed to the outer end of the screw casing, said manually operable mechanism including a cross arm slidably mounted in the mechanism casing, swivel connection for the inner end of the rod and the cross arm, a manually rotated stub 90 shaft journaled in a side wall of the mechanism casing, gear connections between the stub shaft and rod, a star wheel fixed to the stub shaft, a link arm slidably in said casing having a pin associated with the star wheel, a rock shaft and link connections between the rock shaft, cross arm and link arm.

14. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, the connection between the cutter and rod including a socket formed in the outer end of the rod, a shank carried by the cutter extending into said socket, the outer end of the screw casing having a transverse slot therein and said cutter including side blades extending through the slot, said manually operable mechanism including a cross arm slidably mounted in the mechanism casing, swivel connection for the inner end of the rod and the cross arm, a manually rotated stub shaft 105

5 journaled in a side wall of the mechanism casing, gear connections between the stub shaft and rod, a star wheel fixed to the stub shaft, a link arm slidable in said casing having a pin associated with the star wheel, a rock shaft and link connections between the rock shaft, cross arm and link arm.

10 15. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, a center drill fixed to the outer end of the screw casing, the connection between the cutter and rod including a socket formed in the outer end of the rod, a shank carried by the cutter extending into said socket, the outer end of the screw 15 casing having a transverse slot therein and said cutter including side blades extending through the slot, said manually operable mechanism including a cross arm slidably mounted in the mechanism casing, swivel connection for the inner end of the rod and the cross arm, a manually rotated stub shaft journaled in a side wall of the mechanism casing, gear connections between the stub shaft and rod, a star wheel fixed to the stub shaft, a link arm slidable in said casing having a pin associated with the star wheel, a rock shaft and link connections between the rock shaft, cross arm and link arm.

20 25 30 35 40 45 50 55 60 65 16. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, the connection between the cutter and rod including a socket formed in the outer end of the rod, a shank carried by the cutter extending into said socket, the outer end of the screw casing having a transverse slot therein, said cutter including side blades extending through the slot, a center drill connected to the outer end of the screw casing the connection between the center drill and screw casing including a slot formed in the outer end of the screw casing at right angles to the cutter slot, an arm removably mounted in the slot supporting the center drill, said manually operable mechanism including a cross arm slidably mounted in the mechanism casing, swivel connection for the inner end of the rod and the cross arm, a manually rotated stub shaft journaled in a side wall of the mechanism casing, gear connections between the stub shaft and rod, a star wheel fixed to the stub shaft, a link arm slidable in said casing having a pin associated with the star wheel, a rock shaft and link connections between the rock shaft, cross arm and link arm.

17. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, a center drill fixed to the outer end of the screw casing, the connection between the cutter and rod including a socket formed in the outer end of the rod, a shank carried by the cutter extending into said socket, the outer end of the screw casing having a transverse slot therein, said cutter including side blades extending through the slot, the connection between the center drill and screw casing including a slot formed in the outer end of the screw casing at right angles to the cutter slot, an arm removably mounted in the slot supporting the center drill, said manually operable mechanism including a cross arm slidably mounted in the mechanism casing, swivel connection for the inner end of the rod and the cross arm, a manually rotated stub shaft journaled in a side wall of the mechanism casing, gear connections between the stub shaft and rod, a star wheel fixed to the stub shaft, a link arm slidable in said casing having a pin associated with the star wheel, a rock shaft and link connections between the rock shaft, cross arm and link arm.

18. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, the connection between the cutter and rod including a socket formed in the outer end of the rod, a shank carried by the cutter extending into said socket, the outer end of the screw casing having a transverse slot therein, said cutter including side blades extending through the slot, a coil spring surrounding the rod, anchored at its inner end thereto and at its outer end to said screw casing and said manually operable mechanism adapted to retract said rod against the tension of said spring to a position to permit the spring to forcibly eject the rod and cutter carried thereby, said manually operable mechanism including a cross arm slidably mounted in the mechanism casing, swivel connection for the inner end of the rod and the cross arm, a manually rotated stub shaft journaled in a side wall of the mechanism casing, gear connections between the stub shaft and rod, a star wheel fixed to the stub shaft, a link arm slidable in said casing having a pin associated with the star wheel, a rock shaft and link connections between the rock shaft, cross arm and link arm.

19. In a mining machine, a mechanism

- casing; a screw casing journaled therein, a rod reciprocably mounted in the screw casing and extending into the mechanism casing, a cutter carried by the outer end of 5 the rod, manually operable mechanism for reciprocating said rod, a center drill fixed to the outer end of the screw casing, the connection between the cutter and rod including a socket formed in the outer end of 10 the rod, a shank carried by the cutter extending into said socket, the outer end of the screw casing having a transverse slot therein, said cutter including side blades extending through the slot, a coil spring surrounding 15 the rod, anchored at its inner end thereto and at its outer end to said screw casing and said manually operable mechanism adapted to retract said rod against the tension of said spring to a position to permit 20 the spring to forcibly eject the rod and cutter carried thereby, said manually operable mechanism including a cross arm slidably mounted in the mechanism casing, swivel connection for the inner end of the 25 rod and the cross arm, a manually rotated stub shaft journaled in a side wall of the mechanism casing, gear connections between the stub shaft and rod, a star wheel fixed to the stub shaft, a link arm slidably in said 30 casing having a pin associated with the star wheel, a rock shaft and link connections between the rock shaft, cross arm and link arm.
20. In a mining machine, a mechanism casing, a screw casing journaled therin, a rod reciprocably mounted in the screw casing and extending into the mechanism casing, a cutter carried by the outer end of the rod, manually operable mechanism for reciprocating said rod, the connection 35 between the cutter and rod including a socket formed in the outer end of the rod, a shank carried by the cutter extending into said socket, the outer end of the screw casing having a transverse slot therein, said 40 cutter including side blades extending through the slot a center drill connected to the outer end of the screw casing, the connection between the center drill and screw casing including a slot formed in the outer 45 end of the screw casing at right angles to the cutter slot, an arm removably mounted in the slot supporting the center drill, a coil spring surrounding the rod, anchored at its inner end thereto and at its outer end to said screw casing and said 50 manually operable mechanism adapted to retract said rod against the tension of said 55 spring to a position to permit the spring to forcibly eject the rod and cutter carried thereby, said manually operable mechanism including a cross arm slidably mounted in the mechanism casing, swivel connection for the inner end of the rod and the cross arm, a manually rotated stub shaft journaled in a side wall of the mechanism casing, gear connections between the stub shaft and rod, a star wheel fixed to the stub shaft, a link arm slidably in said casing having a pin associated with the star wheel, a rock shaft and link connections between the rock shaft, cross arm and link arm.

against the tension of said spring to a position to permit the spring to forcibly eject the rod and cutter carried thereby, said manually operable mechanism including a cross arm slidably mounted in the mechanism casing, swivel connection for the inner end of the rod and the cross arm, a manually rotated stub shaft journaled in a side wall of the mechanism casing, gear connections between the stub shaft and rod, a star wheel fixed to the stub shaft, a link arm slidably in said casing having a pin associated with the star wheel, a rock shaft and link connections between the rock shaft, cross arm and link arm.

21. In a mining machine, a mechanism casing, a screw casing journaled therein, a rod reciprocably mounted in the screw casing and extending into the mechanism casing, a cutter carried by the outer end of the rod, manually operable mechanism for reciprocating said rod, a center drill fixed to the outer end of the screw casing, the connection between the cutter and rod including a socket formed in the outer end of the rod, a shank carried by the cutter extending into said socket, the outer end of the screw casing having a transverse slot therein, said cutter including side blades extending through the slot, the connection between the center drill and screw casing including a slot formed in the outer end of the screw casing at right angles to the cutter slot, an arm removably mounted in the slot supporting the center drill, a coil spring surrounding the rod, anchored at its inner end thereto and at its outer end to said screw casing and said manually operable mechanism adapted to retract said rod against the tension of said spring to a position to permit the spring to forcibly eject the rod and cutter carried thereby, said manually operable mechanism including a cross arm slidably mounted in the mechanism casing, swivel connection for the inner end of the rod and the cross arm, a manually rotated stub shaft journaled in a side wall of the mechanism casing, gear connections between the stub shaft and rod, a star wheel fixed to the stub shaft, a link arm slidably in said casing having a pin associated with the star wheel, a rock shaft and link connections between the rock shaft, cross arm and link arm.

In testimony whereof I affix my signature.

JOSEPH RECHICHAIR.
